(57) **CLAIM**

The ornamental design for a portion of a shoe sole, as shown and described.

DESCRIPTION

FIG. 1 is a front perspective view of an embodiment of a portion of a shoe sole showing a new design;

FIG. 2 is a rear perspective view of the portion of a shoe sole of FIG. 1; and,

FIG. 3 is a side plan view the portion of a shoe sole of FIG. 1.

Please note that the Figures include broken, solid and dash-dot-dash lines. The area within the solid and dash-dot-dash lines forms the claimed design. The area within the broken lines is environmental. Color, contrast and texture form no part of the claimed design in any of the Figures.

1 Claim, 3 Drawing Sheets
